[57] CLAIM

The ornamental design for an intravenous roller clamp guard, as shown and described.

DESCRIPTION

FIG. 1 is a right rear and top perspective view of an intravenous roller clamp guard showing my new design with the access door in closed position;
FIG. 2 is a top plan view thereof, with the access door in open position, the bottom plan view being a mirror image thereto;

FIG. 3 is a right side elevational view thereof;

FIG. 4 is a front elevational view thereof;

FIG. 5 is a left side elevational view thereof; and

FIG. 6 is a rear elevational view thereof.

The broken line showing of the intravenous tube, clamp and flow adjusting mechanism of FIGS. 1, 3, 5, and 6 is for illustrative purposes only and forms no part of the claimed design.
